ELECTRIC FAN

Frank P. Rodwick, Chicago, Ill., assignor, by
mesne assignments, to The Silex Company,
Hartford, Conn., a corporation of Connecticut

Application December 2, 1950, Serial No. 198,822

9 Claims. (Cl. 230—275)

1

This invention is concerned generally with a portable electric fan and is concerned more particularly with an improved fan guard.

Portable electric fans as generally constructed comprise an electric motor, a fan blade or propeller, a blade or propeller guard, and a base or support for supporting the motor, propeller and guard. The guard generally is constructed in the form of a cage and is made of lengths of wire bent to the proper shape and spot welded together. The spot welding must be done prior to painting, plating, or otherwise finishing the guard to preclude burning of the finish.

Heretofore considerable difficulty has been encountered in assembling and finishing the guard and properly positioning the guard about the propeller. If the guard is assembled and finished prior to being placed about the propeller, it is extremely difficult to assemble the propeller and guard relatively. On the other hand, if the propeller is placed within the guard before complete assembly of the guard it is quite difficult to finish the parts properly.

The broad object of this invention resides in the provision of a new and improved fan guard obviating the above mentioned difficulties.

Another object of this invention is the provision of a fan or propeller guard wherein the elements constituting the guard are welded together to form separate front and back sections, which sections are thereafter painted or otherwise finished and then secured together about the propeller or fan blade by means causing no damage to the finish.

More specifically, an object of this invention resides in the provision of a fan or propeller guard as set forth in the preceding object wherein the front and rear sections of the guard readily snap together without the necessity of tools or fastening elements.

Yet another object of this invention is the provision of a fan guard having readily separable front and rear sections to facilitate cleaning of the fan blade or propeller mounted within the guard.

A still further object of this invention is the provision of a fan guard having separate front and rear sections which readily can be snapped together about a fan blade or propeller wherein an axially extending finger is provided on one of the sections to facilitate assembly of the two sections.

Yet another object of this invention is the provision of a fan guard as set forth in the last preceding object wherein the finger serves also

as a convenient handle for carrying or adjusting the fan.

Another object of this invention is the provision of a fan guard having separate front and rear sections with one of the sections carrying an extending finger to facilitate assembly of the sections wherein like sections can be stacked in nested fashion prior to assembly.

Another object of this invention resides in the provision of a fan guard having cooperable front and rear sections wherein the peripheral portion of one of the sections comprises a substantially cylindrical band having an arcuate bead and the peripheral portion of the other section comprises a discontinuous resilient wire interfitting with said bead.

Other and further objects and advantages of the present invention will be apparent from the following description when taken in conjunction with the accompanying drawings wherein:

Fig. 1 is a front view of a fan embodying the principles of my invention;

Fig. 2 is a side view of the same fan;

Fig. 3 is a perspective view of the front section of the fan guard;

Fig. 4 is a perspective view of the rear section;

Fig. 5 is an enlarged sectional view showing the sections of the fan guard being assembled;

Fig. 6 is a view similar to Fig. 5 showing the sections in assembled relation;

Fig. 7 is a fragmentary detailed view taken substantially along the line 7—7 of Fig. 4 showing the means for attaching the guard to the fan base or support;

Fig. 8 is a view taken along the line 8—8 of Fig. 7;

Fig. 9 is a perspective view showing the nesting of a plurality of front sections of my fan guard prior to assembly; and

Fig. 10 is a perspective view showing the nesting of rear sections prior to assembly.

Referring first to Figs. 1 and 2, a fan 12 embodying the principles of my invention may be seen to comprise a motor casing 14 within which is mounted a conventional electric fan motor, a fan blade or propeller 16, a fan guard generally designated as 18, and a support 20 secured to the propeller guard and supporting the other parts of the fan. The motor casing 14 is shown as the type formed of two sections secured together by a clamping ring 22. The rear of the casing 14 is apertured as at 24 to provide ventilation for the fan motor and a drop cord 26 extends through a suitable aperture in the casing to supply electric power to the motor therein. A conventional

on-off switch 23 is provided near the rear of the casing to control energization of the fan motor. The fan blade or propeller 16 may be of any conventional construction and is shown as having four vanes or blades formed integrally and mounted on the motor shaft 38.

In addition to Figs. 1 and 2, reference should be had also to Figs. 3 and 4 for the construction of the fan guard 18. The fan guard comprises a front section 32 (shown in detached position in dashed lines in Fig. 2) and a rear section 34. The front section 32 includes a peripheral wire 36 having an arcuate extent of somewhat less than 360 degrees. In the particular example shown, the arcuate extent of the wire 36 is somewhat over 270 degrees although the wire may be of greater or lesser extent. As long as the wire is in a discontinuous circle, its inherent resilience allows it to be flexed radially of the circle on which it lies. A wire ring 38 of lesser diameter than the peripheral wire 36 is spaced forwardly of the peripheral wire 36 by symmetrically disposed wire spacers 40. The spacers 40 are shown as being four in number and each such spacer has one end 42 welded to the rear of the ring 38 from which point the spacer curves outwardly and rearwardly to be welded to the peripheral wire 36 along a portion where the spacer and peripheral wire lie in substantially tangent contacting relation as at 44. From the welded junction 44 each spacer 40 curves forwardly and inwardly to the rear of the ring 38 where it is welded as at 46. From the welded junction 46 each spacer 40 extends substantially radially inwardly to a button 48 aligned with the center of the propeller 16 where it does not interfere significantly with the air stream from the fan. The inward extensions of the spacers 40 are turned to form transversely extending fingers 50 about which lugs on the button 48 may be bent to secure the button to the spacers.

A finger 51 comprising a substantially U-shaped length of wire extends rearwardly from the top portion of the peripheral wire 36. The ends of the U forming one end of the finger 51 are welded to the inside of the peripheral wire 36, and the bight forming the other end of the finger is deflected downwardly.

The rear section 34 of the fan guard comprises a substantially cylindrical band 52 formed of a single strip of sheet material, preferably sheet metal, and having its ends secured as by a butt weld 54 to form a continuous ring. The substantially cylindrical band 52 is provided with an arcuate bead 56 concave toward the inner side of the band. This bead is shown in cross-section in Figs. 5 and 6, and in these figures it may be seen that the band 52 is flared slightly outwardly as at 58 and 60 from the bead to facilitate assembly of the fan guard. A pair of substantially V-shaped spacers 62 has forwardly extending fingers 64 which are spot welded to the inner surface of the band 52. The ends of the fingers are located at the rear edge of the bead 56 and provide stops as will be apparent hereinafter. A continuous ring 66, which conveniently is of the same diameter as the ring 38 of the front section is welded to the V-shaped spacers 62 on the rear thereof. Each spacer 62 is provided at its apex with an eyelet 68. Bolts 70 are passed through these eyelets and threaded into apertures in the front of the motor casing to secure the fan guard to the casing.

Assembly of the fan guard 18 with the motor casing 14 and propeller 16 readily is accomplished

after the casing, propeller, and guard have been painted or otherwise finished. The rear section of the guard is secured to the motor casing by the bolts 70 as indicated previously. The propeller then is secured to the motor shaft in any conventional manner and the front section of the fan guard is assembled with the rear section. The lower portion of the peripheral wire 36 of the front section is placed within the band 52 of the rear section and is inserted in the bead 56 therein. The diameter of the peripheral wire 36 is decreased slightly by pushing down on the finger 51, and the front section is forced rearwardly relative to the rear section, the outwardly flared portion 58 of the band 52 camming the peripheral wire 36 to a smaller diameter as seen in Fig. 5. The normal diameter of the peripheral wire 36 is substantially equal to the diameter of the band 52 and is greater than the minimum internal diameter of the band. Therefore, when the wire 36 reaches the bead 56, it springs outwardly to be seated firmly in the bead as shown in Fig. 6. In normal use there are substantially no forces tending to shift the front and rear guard sections axially (i. e. forwardly or rearwardly) of one another and the two sections of the guard remain secured to one another. The stops formed by the ends of the forwardly directed fingers 64 of the V-shaped spacers 62 preclude accidental movement of a part of the peripheral wire 36 past the bead 56. The front section readily may be removed to facilitate cleaning of the fan blade or propeller by pushing down on the finger 51 to free the upper portion of the peripheral wire 36 from the bead 56 and then pushing forwardly on the finger, this being substantially the converse of the assembly operation.

The motor and motor casing 14, propeller 16, and guard 18 are supported by the base 20 as indicated heretofore. The base 20 includes a pedestal 72 which conveniently may be of cast metal. The pedestal is elongated to preclude tipping of the entire fan forwardly or rearwardly and is provided with feet 74 of rubber or other resilient material to prevent marking of a supporting surface. A strip 76 is secured within a transverse slot in the lower portion of the pedestal 72 by any suitable means and extends outwardly and upwardly from both sides of the pedestal and is arcuate at its upper ends to accommodate the cylindrical band 52 of the rear section of the fan guard in juxtaposition. Threaded studs 78 (Figs. 7 and 8) are provided with a bifurcated head 80 which straddles the bead 56. Extending legs 82 of the head 80 fit through apertures on either side of the bead 56 and are peened over to secure the threaded stud 78 to the band 52. The studs 78 are passed through aligned apertures adjacent the upper ends of the strip 76 and knurled knobs 84 are threaded on to the studs to clamp the upstanding ends of the strip 76 against the heads 80 to secure the fan guard, propeller and motor casing in any desired position.

It will be apparent that when the fan is adjusted to direct an air stream up or down that the finger 51 may be grasped to pivot the fan about the studs 78 without the operator's bringing his hands near the propeller. The finger 51 further serves as a convenient handle for carrying the fan about.

As may be seen in Figs. 9 and 10, the front and rear sections 32 and 34 readily are stacked in nested fashion prior to assembly. The peripheral wire 36 of each of the front sections

comprises the outermost portion of each of these sections and the peripheral wires lie above one another. It is necessary only to rotate each section slightly relative to the one on which it rests to provide clearance for the fingers 51, and to provide clearance for the welded junctions 44 between the spacers 40 and peripheral wires 36. Each front section in the stack is supported by the ring 38 lying on top of the spacers 40 of the section immediately below it.

The cylindrical bands 52 of adjacent rear sections 34 lie on top of one another when in stacked array and maintain the rings 66 and V-shaped spacers 62 out of contact with one another. Rotation of each rear section relative to the adjacent rear section provides clearance for the knobs 84.

The fan disclosed herein is simpler and less expensive to construct than those known heretofore, and unsightly markings due to welding after finishing are eliminated. The fan is more effective in use than those known heretofore due to the ease with which the guard is disassembled for cleaning of the propeller and due to the convenient carrying handle provided by the finger used in assembling and disassembling the guard.

Although a particular form of my invention has been shown and described herein, it is to be understood that this is for illustrative purposes only and that my invention is to include all that which falls fairly within the spirit and scope of the appended claims.

I claim:

1. A fan guard for use with a fan having a propeller and means for driving said propeller, comprising a front propeller guard section, a rear propeller guard section, means providing a substantially cylindrical periphery on one of said sections and forming substantially a complete circle, a substantially circular bead in said substantially cylindrical periphery, and a resilient wire disposed substantially peripherally of the other of said sections and interfitting with said bead to maintain said sections securely in assembled relation, said wire being less than 360° in arcuate extent to facilitate flexing into said bead.

2. A fan guard as set forth in claim 1 wherein the means providing the substantially cylindrical periphery of one of said sections is flared to cam the resilient wire of the other section into the bead.

3. A fan guard as set forth in claim 1 wherein a finger is rigidly affixed to the resilient wire to aid in deflecting said wire into the bead of the other section.

4. A fan guard for use with a fan having a propeller and means for driving said propeller, including a rear fan guard section, a front fan guard section, means providing a substantially continuous arcuate periphery on one of said sections, a substantially continuous arcuate bead on said arcuate periphery, and means providing a discontinuous arcuate periphery on the other of said sections interfitting with said bead over an arc greater than substantially 180° to retain said sections securely in assembled relation.

5. A fan guard for use with a fan having a propeller and means for driving said propeller, comprising a propeller guard having front and rear sections; said rear section including a substantially cylindrical peripheral band of substantially 360° in arcuate extent, an inwardly opening arcuate bead extending completely around said band, and a plurality of wire spacers adapted to be secured to the propeller driving means of a

fan, said spacers being welded into the inner surface of said band along one edge of said bead to provide a plurality of stops for positioning said front section; and said front section comprising a wire ring, a plurality of wire spacers welded to said ring, and a discontinuous resilient wire ring having a substantial arcuate extent and welded to said last named spacers and fitting within said bead to secure said front and rear sections in assembled relation, movement of said ring past said bead in assembly being limited by said stops.

6. A fan guard for use with a fan having a propeller and means for driving said propeller, comprising a propeller guard having front and rear sections; said rear section including a substantially cylindrical peripheral band forming substantially a complete circle, an inwardly opening arcuate bead extending substantially completely around said band, and a plurality of wire spacers adapted to be secured to the propeller driving means of a fan, said spacers being welded to the inner surface of said band along one edge of said bead to provide a plurality of stops for positioning said front section; and said front section comprising a wire ring, a plurality of wire spacers welded to said ring, a discontinuous arcuate peripheral wire of substantial arcuate extent welded to said last named spacers and resiliently fitting within said bead to secure said sections in assembled relation, said stops limiting the inserted position of said wire for fitting within said bead, and a substantially axially extending finger welded to said discontinuous peripheral wire to facilitate engagement and disengagement of said wire with said bead.

7. An electric fan comprising motor means having a casing, a propeller driven by said motor means, a rear fan guard section secured to said casing and having a peripheral band forming substantially a complete circle, an arcuate bead extending substantially completely around said band, adjustable means for supporting said motor means, propeller, and rear guard section, and a front guard section having a resilient peripheral wire fitting in the bead of said rear section to maintain said sections in detachable assembled relation, said wire being less than 360° in arcuate extent to facilitate flexing into and out of said bead.

8. A fan guard for use with a fan having a propeller and means for driving said propeller, including a rear fan guard section, a front fan guard section, means providing an arcuate periphery on one of said sections, an arcuate bead on said arcuate periphery and arcuately substantially coextensive therewith, and means providing an arcuate periphery on the other of said sections, one of said peripheries being arcuately substantially continuous and the other of said peripheries being arcuately discontinuous, the means providing the periphery on said other of said sections interfitting with said bead over an arc greater than substantially 180° to retain said sections securely in assembled relation.

9. A fan guard for use with a fan having a propeller and means for driving said propeller, comprising a propeller guard having a front and rear sections; one of said sections including a substantially cylindrical peripheral band forming a periphery, an inwardly opening arcuate bead in said band and substantially coextensive arcuately therewith, and a plurality of wire spacers extending inwardly from said band, said spacers being welded on to the inner surface of said band along one edge of said bead to provide a plurality of

stops for positioning the other of said sections; and said other section comprising a wire ring, a plurality of wire spacers welded to said ring, and a second wire ring welded to said last named spacers and fitting within said bead to secure said sections in assembled relation, one of said peripheries being of substantially 360° in arcuate extent and the other of said peripheries being resilient and having a substantial arcuate extent, movement of the second named wire ring past said 10 bead in assembly being limited by said stops.
